UNITED STATES PATENT OFFICE.

FREDERICK GILBERT MITCHELL, OF HYDE PARK, LONDON, ENGLAND.

APPARATUS FOR TIPPING RAILWAY WAGONS.

Application filed December 8, 1922. Serial No. 605,683.

To all whom it may concern:

Be it known that I, FREDERICK GILBERT MITCHELL, a subject of the King of Great Britain and Ireland, residing at Hyde Park, in the county of London, England, have invented Improvements in or Relating to Apparatus for Tipping Railway Wagons, of which the following is a specification.

This invention has reference to that type of apparatus for tipping railway wagons, which comprises a carrier or cradle on to or into which a railway wagon to be tipped can be run and which can afterwards be partly turned or rotated so as to tip the wagon sideways whilst held in position on the carrier, in order that its contents shall be discharged over one of its sides, and whether or not the carrier with wagons be mounted to turn about a stationary horizontal axis, or is arranged to be raised to a higher level than the ordinary permanent track, in order that the wagon may be tipped at such higher level.

In wagon tipping apparatus of this general type, the carrier or cradle (hereinafter called the carrier) is provided with lateral supporting means against which that side wall of the wagon (hereinafter called for distinction the inner side wall) which will be lowermost during the tipping operation, will then bear. The lateral supporting means consists of a longitudinally extending horizontal member, having its sides normally vertical and is hereinafter called the lateral support. Normally, that is to say, when the carrier and wagon are not tilted, the lateral support is out of contact with the inner side wall of the wagon, and the two are brought into contact with each other, either by moving the said lateral support towards the wagon during the earlier part of the tilting operation, or by moving the wagon laterally on the carrier towards the lateral support, which in this case does not move laterally towards the wagon.

Now the present invention has for its object so to construct the carrier as to enable a wagon supported on or within it to be brought, in a more advantageous manner than heretofore, into a position to bear against the lateral support when the carrier and the wagon thereon are tilted or raised, preparatory to discharging the contents of the wagon over one side of the wagon.

For this purpose, according to the inven-

tion, the portion of the carrier provided with rails on to which a wagon to be tipped is run, is constructed as a movable table or platform mounted to rock or tilt about a horizontal axis located in a longitudinal vertical plane that is to one side of a longitudinal vertical plane passing through the centre of gravity of a wagon and its contents and of the platform on which the wagon is supported and at the side of the last mentioned plane that is remote from the lateral support, so that when a loaded wagon is run on to the platform, the tendency of the platform, if free, would be to tilt in such a manner as to tilt the wagon thereon sideways towards the lateral support. To prevent this tilting movement when the carrier and wagon are in the normal position, the side portion of the platform that would turn downward, if free to do so, (hereinafter called for distinction and brevity, the inner side portion), is arranged to bear against stationary abutment means below such inner side portion. Stationary supporting means may also be provided for the opposite or outer side of the platform. Such supporting means may be constituted by vertical supports having flat upper surfaces upon which the flat underside of the platform can bear. The arrangement is such that when the carrier is in its normal or inoperative position, the tilting platform is held by the stationary abutment means and stationary supporting means in a horizontal position with the rails thereon in alignment with the rails of the permanent track at each end of the carrier so that a wagon can be run on to it, and upon partly rotating the carrier, preparatory to tipping the wagon thereon, or upon raising the carrier to a higher level, preparatory to tipping the wagon thereon, by the means provided for the purpose, the platform will be raised by the carrier whilst its inner side portion, under the action of the loaded wagon, is still bearing against the said stationary abutment means, so that it will become inclined towards the lateral support and gradually tilt the wagon towards such support against which it will ultimately bear. Upon further rotation of the carrier or upon rotation of the carrier after it has been raised to a higher level, the platform will leave the stationary abutment means, the carrier, platform, and lateral support moving as one body under the control of the

means used for rotating the carrier, and of the loaded chains, ropes, bars or equivalent means used for holding the wagon in position on the platform and carrier during the 5 tilting and discharging operation. When the discharging operation is over, the carrier with wagon, under the control of the loaded holding chains or equivalent and the rotating means is rotated in the opposite 10 direction until it assumes a position from which it will return to its original position by gravity. During the latter movement, the inner side of the tilttable platform will, through the rollers carried thereby, or 15 equivalent means, come into contact with the stationary abutment means which will act gradually to return the tilttable platform to the normally horizontal position when the carrier reaches its normal position. 20 The platform then rests on the said abutment means and on the stationary support at the opposite side of the platform.

The lateral support whilst not arranged to be moved bodily towards the wagon, may be 25 mounted to tilt sideways to a limited extent, it may be against the action of a spring or springs, to enable it automatically to bear in an effective manner against the adjacent side of the tilted wagon. For this purpose, 30 it may be mounted in the carrier in such manner that it can turn about a horizontal axis. It may also be arranged to be positively operated through suitable connecting means from lugs or brackets on the inner side portion of the rocking platform.

In the accompanying illustrative drawings, Fig. 1 shows in side elevation, a portion 40 of wagon tipping apparatus of the kind herein referred to, the carrier of which is provided with a rocking platform according to the invention. Fig. 2 shows the platform and part of the carrier in horizontal section taken on the line II-II of Fig. 1, whilst Fig. 3 shows the platform alone in end elevation. Fig. 4 shows a portion of the carrier and platform in longitudinal section whilst Fig. 5 shows such portion in plan. Fig. 6 an end elevation and Fig. 7 a side elevation, showing, to a larger scale than 45 Figs. 1 to 5, one construction of lateral support and means for positively tilting such support about a horizontal axis. Fig. 8 shows in end view, a carrier with rocking platform and self adjustable lateral support. Fig. 9 shows in end elevation, wagon tipping apparatus with a modified arrangement of carrier with rocking platform and self adjustable lateral support. Fig. 10 is a detail view.

50 Referring to Figs. 1 to 5, *a* is a carrier adapted to be tilted about a stationary horizontal axis by hoisting and lowering ropes *b* and hoisting and lowering drums, in a well known manner. *e* is the portion of the carrier provided with rails *f* on to which

a wagon to be tipped is run and which, according to the invention, is, as hereinbefore stated, constructed as a movable or rocking platform. For this purpose, the platform, consisting of a structure comprising connected longitudinal and transverse members *e*¹ and *e*² respectively, suitably braced together by diagonal members *e*³, is provided at its ends with trunnions *g* journaled in bearings in the end members 70 of the carrier *a*. The longitudinal axis of the trunnions *g* is located, as hereinbefore described, so that the inner side portion of the platform, namely that portion at the right hand side of Figs. 1, 2 and 3, would 75 tend to tilt downward, if free. Below this side portion of the platform is a stationary abutment *h*, constituted, in the example, by a concrete block or blocks, against which the inner side portion normally bears through 80 the intervention of rollers *i* mounted in brackets *i*¹ on the underside of the platform, so as then to hold the platform horizontal with the rails *f* thereon in alignment with the rails on the adjacent permanent tracks. 85 Stationary supporting means for the opposite or outer side of the platform are provided, constituted by another concrete block or blocks *k*.

m is a longitudinal lateral support 90 provided at its ends with trunnions at *n* journaled in the end members of the carrier *a* and against which a wagon on the rocking platform will bear sideways when the carrier is lifted by the ropes *b* from the abutment *h*. The lateral support *m* in this example is arranged to be positively turned about the common axis of its trunnions *n* when the inner side portion of the platform is allowed to tilt downward. In the arrangement now being described, the lateral support consists, as shown more clearly in Figs. 6 and 7, of a built-up structure comprising two double channel or section bars *m*¹, *m*² arranged horizontally one above the 100 other and connected together at the inner side thereof by upper and lower longitudinal packing strips or members *m*³, *m*⁴ to which are secured, at intervals, vertical members *m*⁵ whilst to the opposite or outer side of the bars *m*¹, *m*² are connected other vertical members *m*⁶ and vertical bracket plates *m*⁷. The longitudinal and vertical members *m*³, *m*⁴, *m*⁵ at the inner side of the double channel bars may, as shown, be of wood and to the 110 vertical members *m*⁵, hemp rope *o*, rubber belting or the like may be applied on the side that will be next a wagon on the carrier, to serve as a fender or cushioning means for the wagon to rest against when tilted. 115

The built-up lateral support thus constructed is suitably mounted, as by the end trunnions at *n*, to turn about a horizontal axis in the carrier *a*. To each bracket plate *m*⁷, of which there may be two arranged 120

near the opposite ends of the lateral support, is jointed the upper end of a link p to the lower end of which is jointed at p^1 , to an intermediate portion of a lever arm r one end of which is jointed at r^1 , near its connection with the link p , to a fixed part s of the carrier, and the other end of which is joined at r^2 to the upper end of a link t , the lower portion of which is connected, 10 preferably as shown, through a pair of oppositely extending springs u , u^1 and a sliding block v with trunnion v^1 to a lug or bracket w extending from the adjacent inner side of the rocking platform e . The link t , 15 may, as shown, be built up of parallel metal bars with interposed distance pieces t^1 . The arrangement is such that when the inner side of the rocking platform e tilts downward, the lateral support m will be tilted in the carrier a in a positive manner by the link and lever mechanism to bring its supporting surface more or less parallel to the adjacent side of the tilting wagon on the platform, the parts being positively returned to their 20 original position when the rocking platform is afterwards caused to resume its horizontal position by the stationary abutment means h .

The operation of apparatus constructed as described and shown, will be readily understood from what has already been stated herein.

In the modified arrangement shown in Fig. 8, the carrier a with rocking platform e , is provided with a lateral support m , the trunnions n of which are mounted in brackets n^1 fixed to the carrier a so that it is self adjustable to enable it automatically to turn and bear more or less evenly against the sides of a tilted wagon in contact therewith. If desired, one or more springs m^* may be combined with the lateral support, adapted normally to hold the support with its inner side vertical and to return it to that position after being first displaced therefrom by a wagon and then relieved of the side pressure of the wagon.

In the modified arrangement shown in Fig. 9, the carrier a is mounted by means of end trunnions c to turn in bearings carried by stationary end frames 1 above rope holding and lowering drums 2, and the rocking platform e is journalled in the lower laterally projecting end portions a^1 of the carrier a . In this example the inner side portion of the rocking platform e is supported by rollers 3 arranged to bear against stationary transverse girders 4 and carried by the shorter arms of levers 5 pivoted to the platform at 6 and the longer arms of which are connected, as by rods 7, acting through springs 13 to the platform at the outerside of the trunnions g of the platform so that the platform will be restored gradually to its normal horizontal position by the levers when the rollers 3

come in contact with the girders 4, so as thereby to prevent the platform being subjected to shock by sudden contact with the stationary abutment means. The stationary support for the outer side portion of the platform e , is, in this example, constituted by a plate 8 carried by the concrete base 8 a for the tipping apparatus.

The lateral support m , may be suitably connected to loaded holding means, such as chains, rope or equivalent devices, for holding a wagon on the rocking platform during the tipping and return movements. For this purpose in the construction of lateral support hereinbefore more particularly described with reference to Figs. 6 and 7, there may be secured to the upper side of the upper channel bar m^1 , guide brackets 9 for loaded wagon holding chains 9 a that extend downward through the said bar, and are attached at their lower ends to spring caps or holders 10 mounted to slide on vertical guide rods 11 secured to the upper and lower channel bars m^1 , m^2 , coiled springs 12 being arranged between the said caps or holders 10 and upper caps or holders 10 a secured to the upper channelled bar m^1 . In this way, the wagon holding chains 9 a are connected to the lateral support through connecting means that can yield to a limited extent. The guide brackets 9 and the chains 9 a come into contact when the carrier a is tipped and a wagon thereon is thereby brought into contact with the chains.

The loaded wagon holding means used for retaining a wagon on the rocking platform during the tilting and discharge thereof may advantageously be of the kind described in the specification of another application for Letters Patent of even date herewith Serial No. 605,682 and comprising, as shown in Fig. 9, a longitudinal holding bar 14 jointed to links 15 journalled to the brackets n^1 in which the trunnions n of the lateral support m are journalled; and connected to loaded chains 16 which extend upward and pass over guide wheels to balance weights in the usual way, the holding bar 14 being arranged to bear against the upper ends of the end walls of a wagon between the side walls of a wagon, so as to admit of complete discharge of the contents of the wagon.

A tilting platform such as hereinbefore described can be used in various construction of wagon tipping apparatus of the general type referred to, including that described in the specification of British Letters Patent No. 142,198 granted to me, the lateral support described in that specification and the means used for advancing it towards and from a wagon, being replaced by a lateral support of the kind hereinbefore described.

4
What I claim is:—

1. Wagon tipping apparatus of the kind herein referred to, comprising a carrier capable of partial rotation about a horizontal axis, a longitudinal lateral wagon support carried by said carrier and capable of tilting about a horizontal axis, a wagon platform mounted in the lower portion of said carrier to turn about a horizontal axis so located that the platform automatically tends to turn in a direction to bring a wagon thereon towards and against said tiltable wagon support, and abutment means located below the side of said platform that would descend by gravity if free to do so and adapted to maintain the platform in a substantially horizontal position when the carrier is in its lowered normal and inoperative position.
- 10 2. Wagon tipping apparatus according to claim 1, wherein abutments are arranged below said movable platform to support both sides of said platform and adapted normally to hold said platform in a substantially horizontal position.
- 20 3. Wagon tipping apparatus of the kind herein referred to, comprising a tiltable carrier, a rocking platform mounted in its lower portion, abutment means located below said platform and adapted normally to maintain said platform in a substantially horizontal position and means embodying spring buffering devices carried by said platform for engagement with said abutment means when the carrier and wagon return to their normal lower and inoperative position.
- 30 4. Wagon tipping apparatus of the kind herein referred to, comprising a tiltable carrier, an adjustable longitudinal lateral wagon support mounted on said carrier, a rocking platform mounted in the lower portion of said carrier and means connecting said lateral support and rocking platform, adapted to adjust the position of said support in a rotary sense when the platform turns about its axis of motion.
- 40 5. Wagon tipping apparatus of the kind herein referred to, comprising a carrier mounted to tilt sideways about a horizontal axis and having at its ends and at one side portion thereof, upwardly extending members, a lateral wagon support mounted to turn in said end members about a horizontal axis above the wagon support and to bear against the side of a tilted wagon on said support and spring means acting against said support to hold it in normal position but in a yielding manner.
- 50 6. Wagon tipping apparatus of the kind herein referred to, comprising a tiltable car-
- rier, a lateral wagon support adjustable on said carrier, a rocking platform mounted in the lower portion of said carrier, and means embodying spring devices connecting said platform and support and adapted to adjust the position of the latter in a rotary sense when the platform turns about its axis of movement.
- 60 7. Wagon tipping apparatus of the kind herein referred to, comprising a tiltable carrier, a lateral wagon support adjustable on said carrier, a rocking platform mounted in the lower portion of said carrier, and link and lever mechanism embodying spring devices connecting said platform and lateral support and adapted to adjust the position of the latter in a rotary sense when the platform turns about its axis of movement.
- 70 8. Wagon tipping apparatus of the kind herein referred to, comprising a carrier, a lateral wagon support connected thereto, springs associated with said lateral support and counter-balanced flexible wagon holding means connected to said support through said springs.
- 80 9. Wagon tipping apparatus of the kind herein referred to, comprising a carrier having upwardly extending members thereon, a rocking platform for a wagon on said carrier, a laterally arranged spring controlled wagon support mounted to turn in said upwardly extending members about a horizontal axis, counter-balanced flexible wagon holding means connected to said support and means for lifting and turning said carrier about its horizontal axis of movement.
- 90 10. Wagon tipping apparatus of the kind herein referred to, comprising a carrier, horizontally extending end members at one side thereof, stationary supporting means whereby said carrier is mounted to turn about a horizontal axis, an adjustable spring controlled lateral wagon support carried by said upwardly extending member of said carrier and movable about a horizontal axis, a rocking platform carried by said carrier, means independent of said rocking platform adapted to hold the same in a horizontal position when in its normal lowered position, means for lifting and turning said carrier about a horizontal axis and causing a wagon on said carrier to bear against said lateral support and afterwards to further tilt and discharge said wagon, and counter-balanced flexible wagon supporting means connected to said lateral support.
- 100 Signed at London, England, this 27th day of November, 1922.

FREDERICK GILBERT MITCHELL.
